2 SHEETS—SHEET 2.

UNITED STATES PATENT OFFICE.

WILLIAM H. BYWATER AND WILLIAM B. MORRISON, OF SALT LAKE CITY, UTAH.

MEANS FOR AUTOMATICALLY UNLOCKING DOORS.

1,060,317.

Specification of Letters Patent.

Patented Apr. 29, 1913.

Application filed August 12, 1912. Serial No. 714,641.

To all whom it may concern:

Be it known that we, WILLIAM H. BYWATER and WILLIAM B. MORRISON, citizens of the United States, residing at Salt Lake City, 5 in the county of Salt Lake and State of Utah, have invented certain new and useful Improvements in Means for Automatically Unlocking Doors; and we do hereby declare the following to be a full, clear, and exact 10 description of the invention, such as will enable others skilled in the art to which it appertains to make and use the same.

Our invention relates to improvements in means for automatically unlocking doors, 15 the object being to provide simple, positive and quick acting means for releasing the doors of an engine house at the instant an alarm is sent in, so that the doors may be swung open by spring hinges, or other automatic means, to allow of the exit of the horses from the stalls or the engine from its house.

With this object in view, our invention consists in the parts and combination of 25 parts as will be more fully described and pointed out in the claims.

In the accompanying drawings, Figure 1 is a view in elevation taken from the inside, showing our improvement applied to the 30 doors of an engine house. Fig. 2 is a similar view of the releasing mechanism. Fig. 3 is a view of the locking bolts and their releasing spring, and Figs. 4, 5, 6 and 7 are views of several of the parts detached.

35 1 and 2 represent doors, the door 1 being held in its closed position by the door 2. Both doors are provided with spring hinges, springs, weights or other devices for opening them after the bolt mechanism has been 40 released, but as these features for swinging the doors open do not form any part of our invention, we have not illustrated them.

The bolt mechanism is carried by the door 2, and comprises two bolts 3 and 4, the 45 former of which engages a keeper 5, at the top, and the bolt 4 engages a keeper 5 in the sill. Both bolts are mounted in suitable bearings 6, and are off-set at their adjacent ends so as to pass on opposite sides of the 50 block 7 secured to the inner face of the door. Pivotal secured to block 7, is the lever 8, to which both bolts 3 and 4 are loosely connected, so that when the free end of said lever is moved, say up, both bolts will be withdrawn 55 from their keepers, and when moved in the opposite direction, the bolts will be

moved outwardly to engage their keepers. The bolts are automatically retracted by the spring 9 secured at one end to the door 2, and at its opposite end to the lever 8, and 60 they are held in their projected or locking position by the pin 10 on lever 11 resting within a hole 12 formed in the post 13 and passing through the latter. This post 13, shown detached in Fig. 6, is secured preferably by a threaded shank, to the plate 14, 65 which latter carries the bearings 15 and 16 for the sliding rod 17. The rod is preferably made of steel and is mounted in bearings 15 and 16 in line with the hole 12, in 70 post 13, and is adapted to be moved longitudinally by the devices hereinafter described, so as to enter said hole 12 and force the pin 10 on swinging arm 11 out, thus releasing the lever and permitting the spring 75 9 to swing the latter in a direction to retract the bolts.

The bearings 15 and 16 are shown detached in Figs. 4 and 6 respectively, the bearing 15 having holes for its attachment 80 by screws, and the bearing 16 having a threaded shank for its direct attachment to the plate 14. By providing the bearing 16 with a threaded shank, it may be readily adjusted to properly align the rod 17 with 85 the hole 12 in post 13. We prefer however to make the ends of the hole 12 flaring, and the end of the rod 17 adjacent post 13 slightly tapering, so as to insure the entrance of the end of the rod 17 into the hole 12, 90 and into contact with the pin 10, whereby the latter will be driven from the hole thus releasing the swinging arm 11 and lever 8 and permitting the spring 9 to turn the latter in a direction to retract the bolts 3 and 4. 95

Rigidly secured to the rod 17 intermediate the bearings 15 and 16, is the block 18 to which the link 19 is pivotally secured, the opposite end of said link being pivotally attached to the block 20 rigidly secured to 100 the lower end of spring actuated rod 21, and pivotally secured at one end to the said block 20, and at its other end to post 22 on plate 14, is the link 22. It will therefore be seen that both links 19 and 22 are pivotally attached at their upper ends to the block 20, and one, 19, is connected at its lower end to the rod 17 and the other, 20, pivotally connected with the fixed plate 14. The block 20, is as before stated, secured to the 105 lower end of the spring actuated rod 21, which latter is supported by the bracket 23

secured to the door, the opening in the bracket for the passage of the rod, being of a size sufficient to permit the rod to have a lateral or swinging movement, as shown in 5 dotted lines in Fig. 2.

24 is a spring secured at its upper end to rod 21 at a point below bracket 23, and at its lower end to the plate 14, preferably in line with the long axis of rod 21 when the 10 latter is in the position shown in dotted lines in Fig. 2.

Pivottally mounted on post 25 is the latch 26, normally held in position to engage the lower end of block 18, and hold the rod 17 15 in its set position, by the spring 27. This latch is the armature of the magnets 28 which are connected in the gong circuit in series, and when the latter are energized, the armature will be drawn downwardly 20 thus releasing the rod 17 and permitting it to be projected rapidly toward pin 10 on swinging arm 11, and push the latter free of the post 13, thus releasing the arm 11 and permitting spring 9 to act on lever 8 25 as previously explained. When the block 18 is released by the latch 26, the spring 24 pulls the rod 21 downwardly, and as link 22 has a bearing on the fixed plate 14, and the link 19 a bearing on rod 17, the downward 30 movement of the rod 21 straightens out the links from the position shown in full lines to that shown in dotted lines, and the end of the rod coming in contact with the pin forces the latter from its seat in the post 13, 35 thus permitting the spring 9 to retract the bolts. After the alarm has been sounded, the latch 26 assumes its normal position and when rod 17 is retracted by pulling back on handle 29, the shoulder on the latch again 40 engages the block and holds the rod set for the next alarm. The arm 11 is exposed and if from any cause the rod 17 should fail to release the same it can be readily released by a pull or a kick.

45 It is evident that changes in the construction and relative arrangement of the several parts might be made without avoiding our invention and hence we would have it understood that we do not restrict ourselves to the 50 particular construction and arrangement of parts shown and described, but,—

Having fully described our invention what we claim as new and desire to secure by Letters-Patent, is:

55 1. The combination with a door, a bolt thereon, a lever connected with the bolt for projecting same, means tending to retract the bolt and means for holding the lever when the bolt is in its locking position, of 60 automatically actuated means adapted to release the actuating lever and permit the re-tracting means to retract the bolt.

2. The combination with a door, a bolt thereon, a lever connected with the bolt for actuating same, means tending to retract the bolt, and means for holding the lever when the bolt is in its locking position, of a longitudinally sliding rod adapted when released 65 to disengage the lever from its holding means, means for moving the rod longitudinally, and electrically controlled means for holding the rod in its set position.

3. The combination with a door, a bolt thereon, an actuating lever for the bolt, means constantly tending to retract the bolt 75 and means for holding the lever when the bolt is in its locking position, of a longitudinally sliding rod adapted when released to disengage the lever from its holding means, spring actuated mechanism for moving the rod longitudinally in a direction to release said lever, a combined latch and armature for holding said rod in its set position, and a magnet for actuating said armature.

4. The combination with a door, a bolt thereon, an actuating lever for the bolt, means constantly tending to retract the bolt, and means for holding the lever when the bolt is in its locking position, of a longitudinally sliding rod adapted when released, to disengage the lever from its holding means, a spring actuated rod, two links 90 pivotally connected with said spring actuated rod, one of said links being connected 95 with the sliding rod and the other with a fixed support, and an electrically controlled latch adapted to engage a shoulder on the sliding rod for holding the latter in its set position, the construction being such, 100 that when the sliding rod is released, the power exerted thereon through the spring actuated rod and the links will be gradually accelerated.

5. The combination with a door, two bolts 105 thereon, a pivoted lever for actuating both bolts, a spring tending to retract the bolts, an arm carried by the lever and provided with a pin, and a fixed support having a hole to receive the pin, whereby the bolts 110 will be held in their locking position, of an automatically actuated sliding rod, adapted when released to engage said pin and disengage it from its support and thus release the bolt actuating lever.

115 In testimony whereof, we have signed this specification in the presence of two subscribing witnesses.
